RAILWAY TIE AND RAIL FASTENING.

APPLICATION FILED APR. 9, 1908.

917,932.

Patented Apr. 13, 1909.

2 SHEETS—SHEET 2.

UNITED STATES PATENT OFFICE.

WILLIAM P. DAY, OF ALTOONA, PENNSYLVANIA.

RAILWAY-TIE AND RAIL-FASTENING.

No. 917,932.

Specification of Letters Patent.

Patented April 13, 1909.

Application filed April 9, 1908. Serial No. 426,086.

To all whom it may concern:

Be it known that I, WILLIAM P. DAY, citizen of the United States, residing at Altoona, in the county of Blair and State of Pennsylvania, have invented certain new and useful Improvements in Railway-Ties and Rail-Fastenings, of which the following is a specification.

This invention comprehends certain new and useful improvements in metallic ties and rail fastenings therefor, and the invention has for its primary object an improved construction of metallic tie which will embody the combined characteristics of strength and lightness, and improved rail fastenings that may be easily applied to the rails and secured to the ties and that will hold the rail securely against spreading or any sidewise movement, without the use of bolts or the like between the rails and the angle bars. And a further object of the invention is an improved construction of metallic tie that, while being light, may be held securely in position by the ballast, as against any sidewise movement.

With these and other objects in view as will more fully appear as the description proceeds, the invention consists in the construction, arrangements and combination of parts that I shall hereinafter fully describe and then point out the novel features in the appended claims.

For a full understanding of the invention, reference is to be had to the following description and accompanying drawings in which:

Figure 1 is a perspective view of the metallic railway tie constructed in accordance with my invention. Fig. 2 is a transverse sectional view through a rail held in place by my improved tie and fastening device; Fig. 3 is a horizontal sectional view on the line 3—3 of Fig. 2; Fig. 4 is a transverse sectional view through the tie; Fig. 5 is a detail perspective view of one of the rail chairs; Fig. 6 is a similar view of another form of chair and rail joiner that automatically locks the rails and ties together; and Fig. 7 is a bottom plan view of a portion of the tie.

Corresponding and like parts are referred to in the following description and indicated in all the views of the drawings by the same reference characters.

My improved tie, which may be made of steel cast or otherwise formed or of any

other suitable metal as desired, comprises a dished base 1 formed with upwardly and outwardly projecting side flanges 2. A longitudinal web 3 projects upwardly from the base 1 and is preferably integral therewith, and the said web 3 is joined at its ends to the side flanges 2 at the end of the tie by means of transverse webs 4 which not only serve to brace said parts but also afford bearing surfaces for the ballast at the end of the tie so as to prevent the tie from slipping or shifting laterally. The dished formation of the base 1 obviously possesses advantages, as it not only strengthens the tie while at the same time permitting it to be made light, but it also serves to hold ballast to better advantage. Preferably the base 1 is formed at any desired points with drain openings 1^a.

In addition to the longitudinal web 3 and the transverse end webs 4 my improved tie embodies a plurality of transverse webs 5 joining the base to the longitudinal web, there being three pairs of these webs 5 in the present instance, one at the middle of the tie and two between the middle web and the ends of the tie. These webs 5 are for strengthening purposes solely. Near its ends the tie is formed with other transverse webs on opposite sides of the longitudinal web, joining the latter to the base. These last named transverse webs are arranged in pairs, one web of each pair being designated 6 and the other 7.

My improved rail fastenings that are intended to be used along the intermediate portions of the rails embody angle bars 8 designed to embrace the base flange of the rail at one side and extend up along the web of the rail under the head thereof. Each angle bar 8 has a plate 9 depending therefrom and extending transversely as shown, said plate being disposed intermediate of the ends of the base portion of the angle bar so that the lower face of the angle bar on each side of the plate will constitute a downwardly facing shoulder. Preferably the rear edge of the plate 9 curves in from the rear edge of the angle bar and the plate projects inwardly beyond the inner edge of the angle bar, as clearly illustrated in the drawings. The longitudinal web 3 of the tie is formed in its upper edge, between the webs 6 and 7, with a recess 10 and each web 7 is in registry with said recess and terminates 110

flush with the base to form an upwardly facing shoulder 11. Preferably the webs 6 are set back from the recesses, as shown.

A pair of angle bars 8 is arranged on the 5 opposite sides of the rail, with the angle bars resting and fitting in the recess 10 and resting upon and supported by the lower wall of the recess and the shoulders 11 of the adjacent webs 7, and the depending plates 10 9 fit against opposite sides of the longitudinal web 3 and are preferably bolted thereto so as to securely hold the angle bars in place in firm engagement with the rail. One face 12 of each web 7 abuts against one edge of 15 the adjacent plate 9 so as to assist in supporting the same rigidly, while the rear edge of the angle bar abuts against one end of the recess.

The base 1 of the tie is formed with openings 13 upon the opposite sides of the web 3 and between the webs 6 and 7, and the plates 9 extend downwardly into and fit snugly in said openings so as to assist in bracing the parts. It will thus be seen that the rail 25 chairs are held securely to the tie, and that the rails are maintained in perfectly rigid condition.

If desired, the longitudinal web 3 may be formed with a cut-out portion or recess 14 30 in correspondence with the openings 13. And if desired, each angle bar may be formed in its rear side with a lug 15 designed to engage the side of the web 3 which is opposite the side engaged by the plate 9 so 35 as to securely lock the angle bars to the web. For those chairs that are intended to be used at the joints of the rails, the angle bars are extended as at 8^a in Fig. 6, the angle bar being formed at each end with a depending 40 plate 9^a, said angle bar extending from one tie to the next and serving as a bridge piece. The manner of attaching the elongated angle bars 8^a is similar to that before described in connection with angle bars 8.

45 Preferably, as best seen in Fig. 2, the base and web portion of the rails at the angle-bars are incased in fiber in the form of sheets interposed between the angle bars and the rails, as indicated at 16, for the purpose of 50 insulation for signaling purposes and the like and for eliminating sound as far as possible, while at the same time making a cushion for the rails.

From the foregoing description in connection 55 with the accompanying drawings, it will be seen that I have provided a simple, and efficient construction of metallic rail tie and rail fastening by the use of which the rails may be held securely in position and by 60 means of which the rails are capable of withstanding the heavy strains that are imposed upon them in present-day traffic.

As the angle bars are slipped into place and 65 their plates 9 fitted downwardly in the openings in the base of the tie, it is evident that

the lugs 15 together with the plates 9 provide means for embracing the longitudinal web 3, or means whereby the angle bars will engage both sides of the longitudinal web and be thereby held securely in place as 70 against sidewise movement, even without the bolts.

The use of the insulating cushions 16 for the rails tends to deaden the sound of the car wheels as will also the recess 14 and the 75 openings 13, and the peculiar arrangement and construction of parts of the rail chairs effect a permanent and a sure union between the ties and the rails that is durable and not liable to get out of order or require any attention. The end webs 4 which project upwardly some little distance, as best seen in Fig. 2, as well as the dished formation of the base 1 enables the tie to obtain a stable foundation in the ballast and prevents the tie 80 from creeping or shifting laterally.

Having thus described the invention, what is claimed as new is:

1. In a rail tie and fastening, the combination of a tie provided with a longitudinal web, said web being formed at its upper edge with recesses, chairs embodying angle bars and depending plates, the latter being designed to abut against opposite sides of the web and the angle bars resting in said recesses, and means for securing the plates to the web.

2. In a rail tie and fastening, the combination of a tie provided with a longitudinal web and spaced transversely extending webs, the longitudinal web being formed at its upper edge with recesses, rail chairs embodying angle bars and depending plates, adapted to be secured to the longitudinal web on opposite sides of the same and between said transverse webs, the angle bars resting in the recesses and formed with lugs engaging the sides of the longitudinal web.

3. In a rail tie and fastening, the combination of a tie provided with a longitudinal web, said web being formed in its upper edge with recesses, and chairs embodying angle bars and depending plates adapted to be bolted to the longitudinal web, said angle bars fitting in said recesses.

4. In a rail tie and fastening, the combination of a tie provided with a longitudinal web and spaced transverse webs on the opposite sides of the longitudinal web, the longitudinal web being formed in its upper edge with recesses and one of the transverse webs on each side of the longitudinal web terminating at its upper edge flush with the recesses and rail chairs embodying angle bars fitting in said recesses and resting upon said upper edges of the webs, said chairs also embodying depending plates adapted to be secured to the longitudinal web.

5. In a rail tie and fastening, the combination of a tie provided with a longitudinal web

- and spaced transverse webs on opposite sides of the longitudinal web, the longitudinal web being formed in its upper edge with recesses and with one transverse web on each side of said longitudinal web terminating at its upper edge flush with said recesses, said last named webs being set in from the ends of the recess, and means for securing said angle bars to the tie.
6. In a rail tie and fastening, the combination of a tie provided with a longitudinal web and spaced transverse webs on opposite sides of the longitudinal web, said longitudinal web being formed in its upper edge with recesses, and rail chairs embodying angle bars fitting in said recesses and depending plates adapted to be secured to the longitudinal web upon opposite sides thereof, one of said transverse webs abutting against the adjacent edge of the adjacent plate.
7. In a rail tie and fastening, the combination of a tie provided with a longitudinal web said web being formed in its upper edge with recesses, the tie also being provided with two spaced transverse webs on each side of the
- longitudinal web at the recesses one of said transverse webs being set back therefrom and the other set in between the ends of said recesses, and rail chairs embodying angle bars adapted to fit into said recesses and plates adapted to be secured to the longitudinal web upon opposite sides thereof.
8. In a rail tie and fastening, the combination of a tie provided with a longitudinal web and a base portion, the base portion being formed with openings, and rail chairs adapted to be secured to said web and embodying depending plates projecting into said openings.
9. In a rail tie and fastening, the combination of a tie provided with a longitudinal web, and rail chairs adapted to rest in said web and provided respectively with plates adapted to engage one side of the web and with lugs to engage the opposite sides of the web.

In testimony whereof I affix my signature in presence of two witnesses.
